UNITED STATES PATENT OFFICE.

EDWARD BACKUS, OF NEW YORK, N. Y.

DESIGN FOR A BOTTLE.

SPECIFICATION forming part of Design No. 19,892, dated June 10, 1890.

Application filed April 26, 1890. Serial No. 349,687. Term of patent 14 years.

To all whom it may concern:

Be it known that I, EDWARD BACKUS, a citizen of the United States, residing at the city of New York, in the county and State 5 of New York, have invented and produced a new and original Design for Bottles, of which the following is a full, clear, and exact specification, reference being had to the drawings accompanying and forming a part of the same.

10 In the drawings, which fully illustrate the nature of my design, Figure 1 is a side elevation of a bottle showing my new design, and Fig. 2 is a cross-section of the same, these views being all that is considered necessary 15 to display my design.

The leading feature of my design consists in a fluted surface and inwardly-converging lines at the top and base, so that the bottle, when viewed in elevation, will present to the 20 eye the form of the cactus plant.

a is the body portion of the bottle, and *b* is the neck of the same. The body is formed

with a taper to the point where it meets the neck part, and has a slightly-rounded outline at the bottom. Its configuration is irregular, 25 having re-entering angles *c* and radial projections *d*, that extend from end to end of the body portion, and these are alternate and uniform, and present the appearance of a fluted surface when viewed in elevation, and 30 having the effect of a star-shaped body when viewed from the end or in cross-section.

In general configuration the bottle represents the cactus plant.

What I claim as new, and desire to secure 35 by Letters Patent, is—

The design for a bottle, the same consisting of a fluted surface and inwardly-converging lines of the top and base, as shown.

EDWARD BACKUS.
